UNITED STATES PATENT OFFICE.

CHARLES A. CHANNELL, OF CHICAGO, ILLINOIS, ASSIGNOR TO CHANNELL CHEMICAL COMPANY, OF CHICAGO, ILLINOIS, A CORPORATION OF ILLINOIS.

MOP.

1,249,900.

Specification of Letters Patent. Patented Dec. 11, 1917.

Application filed July 20, 1914. Serial No. 851,842.

To all whom it may concern:

Be it known that I, CHARLES A. CHANNELL, a citizen of the United States, and a resident of the city of Chicago, in the county of Cook and State of Illinois, have invented certain new and useful Improvements in Mops; and I do hereby declare that the following is a full, clear, and exact description of the same, reference being had 10 to the accompanying drawings, and to the numerals of reference marked thereon, which form a part of this specification.

Oil mops have come into extensive use for household purposes, and the size and 15 construction thereof has varied to suit different purposes. This invention relates to a variation in the construction of mop heads forming the subject matter of other patents issued to me, the mop in the present case being of triangular shape, facilitating the movement thereof into corners and other difficult places to reach, for the purposes of cleaning the same and collecting dust or accumulated dirt.

20 It is an object of this invention to construct a mop head of triangular shape adapted to receive a mop fabric attached thereon, and with means to receive a handle connected therein by which the mop may be moved around for cleaning purposes.

25 It is also an object of this invention to construct a stamped metal mop head provided with a peripheral channel around which is permanently attached a mop fabric 35 by means of a flexible metal strap, and with a handle socket of improved construction on the top surface of the mop head to receive the handle detachably therein.

30 It is furthermore an important object 40 of this invention to construct a triangular metallic mop head adapted to receive a mop fabric attached therein in a manner greatly simplifying the assembly of the device.

45 It is finally an object of this invention to construct a triangular mop with a mop fabric secured thereto affording a light and durable construction, the peculiar shape of which adapts the same for general use.

The invention (in a preferred form) is 50 illustrated in the drawings and hereinafter more fully described.

In the drawings:

Figure 1 is a top plan view of a device embodying the principles of my invention 55 with the handle detached therefrom.

Fig. 2 is a section taken on line 2—2 of Fig. 1.

Fig. 3 is a fragmentary view partly in section and partly in elevation taken on line 60 3—3 of Fig. 2.

Fig. 4 is a fragmentary section taken on line 4—4 of Fig. 3.

Fig. 5 is a fragmentary rear elevation of the mop head showing the attachment mechanism for the fabric.

Fig. 6 is a section taken on line 6—6 of Fig. 5.

Fig. 7 is a section taken on line 7—7 of Fig. 2.

As shown in the drawings:

The mop head consists of a flat plate of metal 1, having apertures 2, stamped therein, for lightness, and with an upstanding outwardly concave flange 3, formed integral therewith and extending peripherally for almost the entire distance around said plate. At the rear portion of said mop head said flange 3, merges into a vertical flat flanged portion 4, which has stamped outwardly 75 80 therefrom a tongue of metal 5, the position of which, before the mop fabric is attached, being shown in dotted lines in Fig. 6. The mop fabric for attachment to said mop head, consists of a strong tubular portion of fabric 6, associated with which are the strands 7, impregnated with oil.

For the purpose of attaching the mop fabric upon the mop head a strap of flexible metal 8, is inserted through the tubular portion 6, of the mop, with its ends slotted to engage in overlapping relation upon the tongue of metal 5, when in the dotted line position shown in Fig. 6, and after engagement of the strap thereon said tongue is bent 90 upwardly into the position shown in full lines, so that said attaching strap is thereby held securely around the mop, pressing 95

said tubular portion 6, of the fabric into the concave flange 3.

At the forward end or vertex of the mop head, a sharp pointed tongue of metal 9, 5 is struck outwardly and engages into the fabric portion 6, of the mop to hold the same positively retained in position thereon. A portion of the plate 1, is struck upwardly as indicated by the reference numeral 10, and engaging through apertures therein are tongues of metal 11, of an inclined sheet of metal curved on its upper side, as indicated by the reference numeral 12, forming a part of a handle socket. Another member 13, also of metal, is provided 15 with tongues 14, engaging through apertures stamped in the side extensions of said member 12, and together therewith forms a cylindrical handle socket. Said curved portion of metal 12, is stamped inwardly at one point on the top surface thereof, as indicated by the reference numeral 15, to engage the threaded end of a handle 16, the threads of which also engage the corrugations or 20 threads formed in the lower half of the handle socket member 13.

The operation is as follows:

When it is desired to attach the mop fabric to the mop head the flexible strap of 30 metal 8, is inserted through the tubular portion 6, of the mop fabric, having the slots in the ends engaged over the tongue of metal 5, on the mop head, after which said tongue of metal is bent upwardly, so that said metal band holds the tubular portion of the mop fabric rigidly engaged and compressed into the outwardly concave flange 3, of the mop head. For ordinary purposes when it is desired to clean the mop 35 fabric it is merely necessary to shake the same, as the dirt will readily fall therefrom, but after continued use the mop fabric is washed thoroughly in water, but without removal of the mop head, merely detaching the handle 16, therefrom, and after allowing the mop fabric to dry, it is again impregnated with oil.

The construction of the handle socket is peculiar in that instead of corrugating the 40 portion 12, forming the upper half of the socket for its entire length to form engaging threads for the handle, merely a short portion thereof is stamped inwardly as indicated by the reference numeral 15. This 45 portion engages the threads in the handle 16, and together with the threads formed in the lower half or member 13, of the socket, serves to hold the handle rigidly secured in the device. Of course the forward 50 end or point of the mop is that most liable to become detached from the mop head, and accordingly the sharp point of metal 9, is

provided to engage the fabric of the mop, holding the same positively attached at this point. Inasmuch as said point 9, engages 65 the fabric portion below the band of metal 8, the band upon being tightened upon the mop head, serves to force the fabric tightly upon the pointed tongue of metal 9.

I am aware that various details of construction may be varied through a wide range without departing from the principles of this invention, and I therefore do not purpose limiting the patent granted otherwise than necessitated by the prior art. 70

I claim as my invention:

1. In a device of the class described a mop head, a peripheral flange extending therearound, a tongue of metal stamped outwardly from one portion of said flange, a 80 mop fabric having a tubular portion around the upper end thereof, and a band of flexible metal having slotted ends inserted therethrough with the slotted ends thereof engaged over said tongue on the mop head. 85

2. In a device of the class described a triangular mop head having an outwardly concave flange extending peripherally therearound, a portion of said flange at the middle point of one side of the mop head being flat, a tongue of metal struck outwardly therefrom, and a band of flexible metal slotted at its ends adapted to engage a mop fabric to said mop head in said concave channel with the ends of said band engaged over the tongue of metal to hold the mop tightly secured upon the mop head. 90

3. In a device of the class described a mop head of triangular shape having a peripheral flange therearound, a sharp pointed tongue of metal struck outwardly from said flange at one of the vertices of the mop head, a tongue of metal struck outwardly from said flange on the side opposite said vertex, and a band of metal engaged around said flange holding the mop fabric closely engaged therewith with the pointed tongue of metal projecting into the mop fabric and with the ends of said band engaged over said tongue of metal stamped from the flange on the side portion of the mop head. 105

4. In a device of the class described a mop head comprising a flat plate provided with an upstanding flange extending therearound, an integral outwardly bent upwardly projecting member on said flange, a mop fabric, and a slotted strap associated with said mop fabric and engaging over the upper end of the projecting member of the flange to hold the mop fabric in position upon the mop head. 115

5. In a device of the class described the combination with a mop head comprising a flat plate provided with an integral periph-

eral upstanding concave flange of a mop fabric having an attaching member associated therewith, outwardly bent upwardly projecting means integrally formed on said flange to engage said member and secure the mop fabric in position against the flange.

In testimony whereof I have hereunto sub-

scribed my name in the presence of two subscribing witnesses.

CHARLES A. CHANNELL.
